SWIVEL

Robert P. Fisher, Los Angeles, Calif.

Application August 28, 1944, Serial No. 551,579

3 Claims. (Cl. 255—25)

1

This invention relates to a device for supporting a rotating member, and particularly to one in which fluid under pressure must be transmitted to a tubular rotating member. Such devices, commonly called swivels, are extensively employed in the oil industry for supporting the rotating drill string used in the rotary process of oil well drilling.

It is an object of this invention to provide a swivel of improved and simplified construction.

It is another object of this invention to provide a swivel capable of supporting a great weight of a long string of drill pipe, and embodying for this purpose, a plurality of thrust bearings employing rolling bearing elements.

In addition to supporting the drill string, the swivel provides a connection between a stationary conduit connecting a source of supply of drilling liquid and the drill string. Such fluid carries a large amount of abrasive material and must be supplied under pressure, which is frequently of the order of a thousand pounds per square inch. The problem of preventing leakage of such fluid between the rotary and non-rotary elements of the swivel is thus a difficult one. It is thus another object of this invention to provide a swivel having improved means preventing leakage of the drilling fluid.

This invention possesses many other advantages, and has other objects which may be made more clearly apparent from a consideration of one embodiment of the invention. For this purpose there is shown a form in the drawings accompanying and forming part of the present specification. The form will now be described in detail, illustrating the general principles of the invention; but it is to be understood that this detailed description is not to be taken in a limiting sense, since the scope of this invention is best defined by the appended claims.

Referring to the drawing:

Figure 1 is an axial section through a swivel embodying the invention, the innermost or sealing member being shown partly in elevation;

Fig. 2 is a sectional view, partly in elevation, taken along plane 2—2 of Fig. 1;

Fig. 3 is a cross sectional view taken along plane 3—3 of Fig. 2; and

Fig. 4 is a detail section of the seat which supports the sealing member.

As shown in Fig. 1 of the drawing, the swivel comprises outer and inner tubular members 1 and 2 in telescopic relationship. The outer member 1 is adapted to be suspended by a bail 3. The inner member 2 is rotatably supported on the

2

outer member 1 by a plurality of rolling bearing elements 4; the drill string 5 is secured to its lower end. Drilling liquid is supplied to the drill string through a goose neck 6, a packing member 7 being provided to prevent escape of this liquid between the members 1 and 2.

Referring in more detail to the swivel, the outer member 1 is provided with reduced threaded portions 10 and 11 respectively at its upper and lower ends. A cap or closure member 12 is threaded in the upper portion 10 and provides a chamber 13 which communicates with the passage 14 which extends axially through the inner member 2. The goose neck 6 is threaded into cap 12, opening into chamber 13; it is adapted to be connected with the source of supply of drilling fluid by a flexible conduit (not shown). The bail 3 is pivotally secured to cap 12 at diametrically opposite points on the outside thereof by shoulder screws 15 threaded into the cap 12. The bail 3 serves to suspend the swivel and the drill 5 from a hook 16 as is well understood.

The bore 17 of member 1 has a plurality of axially spaced bearing races 18 formed therein to accommodate the bearing elements 4. These races are so formed that the bearing elements 4 which may be in the form of balls, extend therefrom into cooperating bearing races 19 formed in the exterior surface 20 of the inner or rotary member 2 and which is telescoped in bore 17. Since the elements 4 are spherical, each of the races 18, 19, is of hemispherical cross section. In this way the balls 4 are in shear between members 1 and 2 and transfer axial force between the members. Further, any lateral force is transferred between the members by the engagement of balls 4 with the bottoms of the races. Thus any tendency of the members to cramp due to axial misalignment, as by twisting and side thrusts on drill string 5, is prevented. Since the balls 4 are arranged in longitudinally spaced series of races that extend over a considerable distance in an axial direction, the guiding of the rotary member 2 is effected without any danger of cramping.

The lower reduced end 11 of member 1 has a guide member 21 threaded thereon with a bore 22 for accommodating the lower extension 23 of member 2 which is of reduced diameter. Member 21 has an outside diameter which is slightly greater than the outside diameter of the outer member 1, thus providing an upwardly directed shoulder 24 for supporting a sleeve 25 telescoped over the exterior of member 1. Cap 12 similarly has a greater outside diameter than member 1

and thus cooperates with member 21 to secure sleeve 25 in place. As shown in Figs. 2 and 3, sleeve 25 is for the purpose of retaining plugs 26 in place in member 1. These plugs 26 serve to close openings 27 which extend from the exterior of member 1 into races 18. These openings 27 permit the balls 4 to be placed in their cooperating races 18, 19 after the members 1 and 2 have been assembled, or to permit removal of the balls 4 for replacement, or in order that members 1 and 2 may be disassembled.

The bore 14 of the inner member 2 has a threaded portion 28 at its lower end for attaching the drill string 5 to the member, and is of enlarged diameter as at 29 for accommodating the packing member 7. This packing member comprises a hollow mandrel 30 rotatably supported in bore 29 as by a seat 31 and having a head 32 positioned in bore 17 above the inner member 2. The mandrel 30 is restrained against rotation as by a pin 33 threaded into member 1 and engaging a notch 34 in head 32. For sealing between the head 32 and the wall of bore 17, one or more spring rings 35 such as are commonly known as piston rings may be provided, being accommodated in annular grooves 36 formed in the head. These rings are preferably of the "step-cut" type, as shown in Fig. 1.

Pressure in chamber 13 acts on head 32 to force mandrel 30 to its seat 31 and it is necessary that leakage be prevented at this point to prevent escape of the drilling fluid from the swivel. Accordingly, the surface 37 which joins passage 14 with its enlarged portion 29 is inclined downwardly and inwardly, and the lower end of mandrel 30 is correspondingly inclined as at 38 (Fig. 9) so as to seat therein and form a liquid tight joint.

Since there is relative rotation between mandrel 30 and the member 2 in which it is seated, and the force urging the mandrel to seal may be considerable, it is desirable to provide means for reducing the wear of the seating surfaces 37 and 38. For this purpose, means are provided forming a ball thrust bearing for supporting mandrel 30. Thus, an annular groove 40 is provided about mandrel 30 at such a position that balls 41 accommodated in the groove will bear upon inclined surface 38 as well as upon the wall of the enlarged passage 29 (see Fig. 4).

Groove 40 is cut slightly higher than its desired position with respect to surface 38, where mandrel 30 is made. Thus when the mandrel is first put in use with member 2, the full force urging mandrel 30 downward urges surface 38 against surface 37 so that relatively rapid wear occurs to quickly cause these surfaces to properly seat. After such initial wearing in has taken place, this force is transmitted between the mandrel 30 and member 2 by the balls 41 bearing on surface 37, and this wear is thus substantially checked. A very small amount of wear occurs on the ball race 40 and also on that area of surface 37 contacted by the balls 41, and this is sufficient to insure the maintenance of a liquid tight seal between surfaces 37 and 38. By so reducing the wear between these surfaces, the useful life of the mandrel 30 and also of the member 2 is greatly increased.

I claim:

1. In a swivel, a stationary member having a bore, a rotatable member having an exterior cylindrical surface closely spaced in telescopic relation with said bore, there being opposed aligned circumferential grooves respectively in said bore and said surface, forming cooperating bearing races, rolling bearing elements interposed between said members in said races, said rotatable member having an axially extending through passage, said bore extending beyond said rotary member, means on said stationary member closing the extending portion of the bore, a tubular sealing element having a head in said bore extension, means sealing between said head and said extension, and means forming a seat in said passage for supporting and sealing against said element.

2. In a swivel, a stationary member having a bore, a rotatable member having an exterior cylindrical surface closely spaced in telescopic relation with said bore, there being opposed aligned circumferential grooves respectively in said bore and said surface, forming cooperating bearing races, rolling bearing elements interposed between said members in said races, said rotatable member having an axially extending through passage, said bore extending beyond said rotary member, means on said stationary member closing the extending portion of the bore, a tubular sealing element having a head in said bore extension, means sealing between said head and said extension, means forming a seat in said passage for supporting and sealing against said element, and means forming a seat in said passage for supporting and sealing against said element.

3. In a swivel, a stationary member having a bore, a rotatable member having an exterior cylindrical surface closely spaced in telescopic relation with said bore, there being opposed aligned circumferential grooves respectively in said bore and said surface, forming cooperating bearing races, rolling bearing elements interposed between said members in said races, said rotatable member having an axially extending through passage, said bore extending beyond said rotary member, means on said stationary member closing the extending portion of the bore, a tubular sealing element having a head in said bore extension, a snap ring interposed between said head and said extension for sealing therebetween, means forming a seat in said passage for supporting and sealing against said element, and means restraining said element against rotary movement with respect to one of said members.

4. In a swivel, a stationary member having a bore, a rotatable member having an exterior cylindrical surface closely spaced in telescopic relation with said bore, there being opposed aligned circumferential grooves respectively in said bore and said surface, forming cooperating bearing races, rolling bearing elements interposed between said members in said races, said rotatable member having an axially extending through passage, said bore extending beyond said rotary member, means on said stationary member closing the extending portion of the bore, a tubular sealing element having a head in said bore extension, a snap ring interposed between said head and said extension for sealing therebetween, means forming a seat in said passage for supporting and sealing against said element, and means restraining said element against rotary movement with respect to one of said members.
